UNITED STATES PATENT OFFICE

161,852

MATERIAL DISPENSER WITH SPOUT

Donald R. Meeder, Blue Springs, Mo.

Application May 29, 1950, Serial No. 10,254

Term of patent 14 years

(Cl. D52—2)

To all whom it may concern:

Be it known that I, Donald R. Meeder, a citizen of the United States, residing at Blue Springs, in the county of Jackson and State of Missouri, have invented a new, original, and ornamental Design for a Material Dispenser with Spout, of which the following is a specification, reference being had to the accompanying drawing, forming a part thereof.

Fig. 1 is a side elevational view of a material dispenser with spout, showing my new design.

Fig. 2 is a top plan view thereof.

Fig. 3 is a front elevational view thereof; and

Fig. 4 is a rear elevational view of the material dispenser with spout.

I claim:

The ornamental design for a material dispenser with spout, as shown.

DONALD R. MEEDER.
